DUPLEX SYSTEM OF TELEPHONY

Application filed February 8, 1927, Serial No. 168,671, and in Germany February 26, 1926.

I filed an application Number 31,515 in Germany, February 26, 1926.

High frequency telephony over power lines of electrical generating stations involves in the majority of cases telephonic communication between several stations over existing high potential air lines. For economical reasons the arrangements are so made that in any kind of signalling between the two stations which are included in the network the same waves are used. This problem of duplex communication is, in general, solved by using different waves, that is, oscillations of different frequency for the transmitter and the receiver. In general, the outgoing or sending wave of one station during signalling is the receiving wave of the station communicated with, and vice versa. If it is necessary for any two high frequency stations from a large number of stations connected to the high potential network, to communicate with each other, it is necessary that each station be supplied with means for permitting different wave lengths to be used in such communication. By this it is meant that means must be provided at each station whereby the exchange or interchange of transmitted and received waves may be made. When signalling between stations it is necessary that the sending and receiving waves of a station should be opposite to what they are at the station to which the signals are sent.

The transmission oscillation circuits carry radio frequency currents of considerable amplitude, so that a change in its wave would be attended with the necessity, normally, of relays, and these would have to be built to meet requirements as regards sparking and arcing. Ordinary means to suppress sparking are useless in the case of radio frequency circuits. Even if the portions of the oscillation circuit to be connected are disposed in a suitable manner with the end in view of minimizing the potentials arising across the relay contacts, the ordinary feeble-current relays will not be usable.

In accordance with the present invention the change-over to another wave is accomplished while the oscillation circuits of the

transmitter carry no current, and for this purpose, in some cases there is required a comparatively simple dependence of the wave relay upon the calling device.

Circuit arrangements as described above are suited for use for transmission systems in which the change of wave length occurs at the calling station, and also for systems wherein the change of wave length is accomplished at the station called.

This invention will be more fully understood in connection with the description of the drawing, wherein:

Figure 1 shows diagrammatically a preferred embodiment of my invention;

Figure 2 illustrates diagrammatically another embodiment thereof in which a relay interrupter and a stepping mechanism device are utilized; while,

Figure 3 diagrammatically illustrates my invention as utilized in a circuit in which the transmitter exciter runs constantly.

In the arrangement shown in Figures 1 and 2 of the drawing, the frequency to be generated by the oscillation circuit depends upon whether the oscillation circuit includes LC_1 or LC_1, C_2 . Whether or not C_2 is included in this circuit depends upon the position of the switch i in each case because winding U can only be energized to close u when i is closed. The position of the switch i depends upon whether or not signals from another station are coming in to energize the actuating winding J to move i into the closed position. In Figures 1 and 2 then the frequency generated can be determined from the calling station.

Referring to Figure 1, the motor M , utilized for driving the transmitter E , which is here represented as a high frequency alternator, is started by closing switches g_1, g_2 . Closing the switches g_1, g_2 connects the motor M to source 10 and starts the motor M rotating. First assume no signal is being received in J . J is deenergized, i is open, and U cannot be energized by way of $g_2, i, 11$, nor by way of $h, 11$. The frequency of the oscillations generated by E is determined by LC_1 .

Now assume that a calling signal is being received at this station and that the winding

J is energized to close both contacts i . The switches i and switches g_1, g_2 are closed and this places the magnet winding H in series with the source of energy 10, which energizes the winding H. This closes the switch contact h . Since the switches g_1, g_2 are closed magnet winding U is energized through the circuit g_2, i, U , battery 11, etc. Energizing winding U closes contact u and adds capacity C₂ to the transmitter oscillation circuit LC₁. As will be seen, the frequency of the transmitter oscillation circuit will be changed since the tune of said circuit has been changed by adding C₂ thereto, as described above. The holding magnet H is, as indicated above, energized and closes a holding circuit $h, 11, U$ through the magnetic winding U to maintain switch contact u in the closed position.

It is necessary that the transmitter circuit be closed at u before the generator produces oscillations since, as indicated above, the object of this invention is to prevent changes being made in the oscillation generator circuit during operation. No additional means need be provided here to retard wave generation by E since the change-over relay U will be operated before the motor M has attained sufficient speed to run the generator at a speed at which oscillations of appreciable potential are produced in LC₁. Upon disconnection of the equipment by opening switches g_1, g_2 , the holding relay H remains connected in parallel with the terminals of the motor M. This relay H in practice will be constructed so as to be very sensitive, and will remain energized during the entire coasting time of the motor M and generator E, that is, the time during which a potential still exists across the terminals of the motor M driving the transmitter E. When the potential across the terminals of the motor M driving the transmitter E has become very low, and also when generation of oscillations by E has ceased, then relay H will be come deenergized and will permit h to open. This opens the circuit through winding U, removing capacity C₂ from the oscillation circuit so that such oscillation circuit will be tuned by LC₁ only to generate the original wave. The contact i renders the wave change dependent upon the direction of the calling since i is directly controlled by winding J. It is immaterial, as can be seen from the above description, whether the transmitter is equipped with an alternator or with a thermionic generator. In case thermionic oscillation generators are utilized, the relay H may be connected with the terminals of a machine supplying the plate potential.

In the arrangement of Figure 2 assume first that J is not energized. When the switches g_1, g_2 are closed the generator develops oscillations of a frequency determined by LC₁ since i is open and U has no complete circuit through source 11. How-

ever, simultaneously with the closing of the motor circuit by way of g_1 , the switch g_2 is closed. If i is still open, then no change can be effected in the circuit LC₁, C₂.

Now assume that signals are received in J. When g_2 is closed a circuit g_2 , the arm of W, W, i , battery 11, and winding D is completed. The winding D is energized and the arm connected with the plunger of D moves ratchet wheel K forward one step, thereby closing the circuit of the changeover relay U. Leaving its initial position the arm connected with K opens the circuit of the driving magnet D. The motor M starts slowly and the relay U, energized by way of i , the arm of W, W, U and 11, operates with sufficient speed so that the oscillation circuit L, C₁, C₂ is completed, that is, C₂ added to said circuit, before the transmitter E generates oscillations of appreciable amplitude.

When it is desired to stop the generator, switches g_1, g_2 are opened to stop the driving motor M. A circuit B, U, D is closed, and the driving magnet D is energized intermittently by the running chopper or interrupter B. The interrupter B may be of any known type. The arm connected with the plunger of D is actuated and K is simultaneously stepped forward during the operation of the circuit interrupter, in this manner returning said arm to its initial position after a certain number of steps. It is only in this initial position that both the circuits of the wave changing relay U and the driving magnet D are switched off. The time for returning the arm of W to this initial position is so arranged as to be longer than the slowing down period of the driving motor. The circuit through U and 11 is completed, as long as i is closed, until the arm of W reaches its initial position. Naturally the circuits can be so arranged that the excitation of the change-over relay can be effected after the switches g_1, g_2 are in the state of rest. Likewise, it makes no difference whether the relays are operated by open or closed circuit working.

Here the switch u is never operated while oscillations are being developed in the circuit LC₁, C₂. Here also the frequency developed may be determined by the calling station since the position of u depends on whether J is energized or not.

In Figures 1 and 2 the frequency generated is determined by the position of i . The position of i in turn depends upon whether signals are coming in from another station or not. In other words, the frequency produced by E and associated circuit is controlled in part at least by another calling station. In the arrangement of Figure 3, to be described hereinafter, the frequency developed is determined at the sending station, i. e., at E, and is not determined at the calling station.

In Figure 3 the changing-over of the wave lengths takes place with the driving motor of the transmitter running. The present invention however provides means whereby the 5 changes in the frequency determining circuit are made before said circuits are appreciably energized by the generator or after the amplitude of the oscillations produced therein due to excitation by the generator has 10 fallen to a low value or the oscillations have stopped.

This figure illustrates the case where the high frequency alternator E, driven from motor M, and which serves for exciting a 15 transmitter amplifier 12, runs constantly. This generator E may supply, for instance, the input circuit of the power amplifier 12 with a radio frequency potential either directly or by way of transforming means. If 20 here a change in wave-length is to be effected while the set ME is running, care must be taken to insure that the transmitter is prevented from exciting 12 and the circuit LC₁ before said change is made. This 25 may be accomplished by short-circuiting E by closing the switch t₁. In the drawing, as shown, the relay U in addition to controlling the switch u₁ for the wave-change, controls also the working contacts u₂ and u₃. The relay T controls the working contacts t₁ and t₂, the relay V operates a make-and-break contact v which, in the drawing, is shown to be in its position of rest (left-hand position) at which position the relay V is 30 presumed to be deenergized.

To produce one wave or frequency the two double-throw switches s₁, s₂, are changed over conjointly into their left-hand position. To produce the other wave-length or 40 frequency, they are again conjointly changed over into the right-hand position. These switches may be coordinated with the telephone receiver in this manner that, when the same is being lifted off, they are caused to 45 move into their working position on the left-hand side, and when replacing the receiver, they are moved to their position of rest towards the right-hand side.

If the double-throw switches s₁, s₂, for initiating wave-change, are moved to the left, the winding of relay T will be energized by current from 11 by way of v and s₁. The armature of relay T will actuate its switches t₁, t₂. By the closure of t₁ the transmitter 50 is rendered inoperative, due to the short circuit completed by way of t₁, and the oscillation circuits LC₁, C₂, in which the switching operations are to be performed, will carry no current. The simultaneous closing of contact t₂, energizes the winding of the relay U by way of t₂, the switch s₂ moved over to the left-hand side, battery 11, resistance Wd, the winding of U, and back to t₂. The armature of U closes contacts u₁, u₂ and u₃. This 60 wave-change accomplished by u₁ therefore

takes place only after E has been short circuited by t₁.

The closing of the contact u₂ completes a holding circuit by way of u₂, battery 11, and resistance Wd through the winding of relay U so that this winding remains energized, irrespective of whether the contact t₂ is opened again or not. The closing of contact u₃ causes energization of the winding of relay V by way of circuit u₃, battery 11 and the winding of V. When V is energized the contact v is pulled to the left so that the circuit for T, which had previously been closed by way of the contact s₁ in the left-hand side, is now opened. The result is that after u₁ is closed t₁ opens so that wave generation is resumed. The frequency of the oscillations generated is determined by LC₁ and C₂. 75

Now, if the frequency of the wave generated is to be changed again, i. e., determined by LC₁ then the switches s₁, s₂ are moved to the right-hand position as shown. Since v is now in its right-hand position, owing to the continued energization of the winding of V the winding of T will be energized by current from 11 by way of the two switches v and s₁ which has been moved to the right-hand position. The winding of T being energized will cause interruption of the wave generation by virtue of the fact that t₁ will be closed. Furthermore, t₂ will be closed, and the winding of U will be short-circuited by way of a circuit through t₂ and the switch s₂ which is in the right-hand position. The contacts associated with V open. Opening of the contact u₁, restores the oscillation circuit LC₁ to the position as illustrated. That is C₂ is no longer included in this circuit. The opening of the contact u₂ separates or opens the holding circuit which still existed between the end of winding U and the battery 11. The opening of contact u₃ breaks the circuit through the winding of V. v is moved over into the left-hand position as illustrated interrupting the circuit through the winding of T. t₁ is opened again, and the short circuit removed from E. The generation of waves by E and the amplifier at a 90 frequency determined by LC₁ is resumed. The change in the tune of the circuit has in all cases been effected in the absence of current flow in the frequency determining circuit. 95

I claim as my invention:

1. In radio frequency communication systems including an oscillation generator having a frequency determining circuit and means for changing the tune of said circuit, switching means for putting said oscillation generator into operation, means associated with said switching means and with the frequency determining means in the circuit of said oscillation generator for insuring that the change in the tune of said circuit is com- 100 105 110 115 120 125 130

pleted before said generator develops oscillations in said circuit of appreciable amplitude, and means for preventing change in said frequency determining circuit from being made when said generator is stopped until said generator stops producing oscillations in said circuit.

2. In radio frequency communication systems comprising a plurality of stations, each including an oscillation generator having a frequency determining circuit and means for changing the tune of said circuit, and a receiver adapted to receive signals from a similar station, switching means at said station for putting said oscillation generator into operation, means associated with said receiver and with the frequency determining means in the circuit of said oscillation generator for preventing the tune of said circuit from being changed while said generator remains in operation except when signals are received on said receiver, and means at said station for preventing a change in the tune of said frequency determining circuit from being made when said switching means is actuated to put said generator out of operation until said generator has stopped producing oscillations of appreciable amplitude in said frequency determining circuit.
3. In a high frequency radio communication system comprising a plurality of stations, each including an oscillation generator, a frequency determining circuit connected with said generator and means for changing the tune of said circuit, and a receiver to receive signals from a similar station, the receiver and transmitter operating at different frequencies, means at said station for starting said generator whereby said generator normally produces a predetermined frequency, means connected with said receiving means and actuated by signal received therein for preparing means to change the tune of said frequency determining circuit and the frequency of the oscillations produced when said generator is started, said last two means including means whereby changes in the tune of the frequency determining circuit are made before the generator develops oscillations of appreciable amplitude, and means associated with said circuit preparing means and frequency determining circuit changing means for inhibiting changes in the tune of said frequency determining circuit when said generator is stopped until the oscillations produced in said circuit are of small amplitude.

4. A high frequency radio communication system including an oscillation generator, a tuned circuit connected with said generator to determine the frequency of the oscillations generated, an additional tuning element, switching means for connecting said additional element in said circuit to change the tune thereof and the frequency of the oscillations generated, an actuating relay connected

with said switching means, said relay having an energizing circuit including a normally open contact, means at said station for starting said generator and for simultaneously closing said normally open contact when said generator is started, whereby said actuating relay is energized to actuate said switching means, include said additional element in said frequency determining circuit to change the tune thereof, and to change the frequency of the oscillations developed, means for preventing the development by said generator of oscillations of appreciable amplitude before the switching action is completed, and means associated with said relays for preventing said switch from being opened by the deenergization of said relay circuit when said generator is stopped until the oscillations produced in said circuit are of small amplitude.
